UNITED STATES PATENT OFFICE.

HENRY C. DORN, OF MILWAUKEE, WISCONSIN.

COMPOSITION BOARD.

Application filed December 29, 1920. Serial No. 433,875.

To all whom it may concern:

Be it known that I, HENRY C. DORN, a citizen of the United States, and resident of Milwaukee, in the county of Milwaukee and State of Wisconsin, have invented new and useful Improvements in Composition Board, of which the following is a description, reference being had to the accompanying drawings, which are a part of this specification.

This invention relates to improvements in composition board.

Composition board now in general use is of a solid construction and is considerably thinner than ordinary lumber on account of its comparatively heavy weight and cost to manufacture.

The thinness of the ordinary composition board is objectionable in the building line as the thin material will give and warp easily and does not provide sufficient insulating qualities for building purposes. Furthermore the ordinary composition board is not suitable for outside work which is subjected to all climatic conditions.

It is one of the objects of the present invention to overcome the above mentioned objectionable features and provide a composition board which may be used for inside or outside work and which may be made in thicknesses corresponding to the thickness of standard lumber.

A further object of the present invention is to provide a composition board having inner air spaces which impart desirable insulating qualities thereto.

A further object of the invention is to provide a composition board of water proof construction which may be safely used for exterior work.

A further object of the invention is to provide a composition board adapted for use in building exterior stucco or plaster work.

A further object of the invention is to provide a composition board which is of simple construction, is strong and durable and which may be easily worked like ordinary lumber.

With the above and other objects in view the invention consists of the improved composition board and its parts and combinations as set forth in the claims, and all equivalents thereof.

In the accompanying drawing in which ⁵⁵ the same reference characters indicate the same parts in all of the views;

Fig. 1 is a side view of a wall formed of the improved composition board, parts broken away and other parts in section to ⁶⁰ show interior construction;

Fig. 2 is a transverse sectional view there-
of on a larger scale, taken on line 2—2 of Fig. 1;

Fig. 3 is a transverse sectional detail view ⁶⁵ on a larger scale of the insulating portion of the board;

Fig. 4 is a vertical sectional detail view illustrating manner of constructing an in-
side and outside wall; and ⁷⁰

Fig. 5 is a perspective view of a piece of the board adapted for stucco or plaster work.

Referring to the drawing the numeral 8 indicates a portion of a panel formed of the improved composition board which may ⁷⁵ be of any size or shape desired. The board is formed of an outer portion 9 of cement and asbestos, an inner portion 10 of asbestos, plaster Paris and magnesia, and an intermediate air space or insulating portion ⁸⁰ 11 formed of lengths of straw 12 coated with any desirable material 12' to render the straw as fire-proof as possible. The straw is sewed together in sections by lines of stitches 13 to form mat like structures which ⁸⁵ extend at right angles to and adjacent each other and in spaced relation in sections and are covered on one side with the cement and asbestos, and on the other side with asbestos, plaster Paris and magnesia in fluid state. ⁹⁰ The said composition portions will pass be-
tween the spaces of the straw sections as in-
dicated in Fig. 3, and also between the straw section spaces and form an integral structure ⁹⁵ as shown in Figs. 1 and 2.

The lines of stitches 13 preferably extend horizontally and are connected together at the edges of the mat like structure by cords 13' which hold the horizontal stitch lines in place and also provide for more securely ¹⁰⁰ fastening the board or panel to its support by driving nails or staples therethrough.

For building purposes the boards or panels may be of the standard thickness of seven eighths of an inch and be formed with rab-
beted edges 14 which overlap each other and are secured to the timber 15 by staples 16. The inside surface of the outside boards or ¹⁰⁵

panels are coated with asphaltum 17 to keep out the moisture.

Boards or panels for inside work may be made of five eighths inch or any other thickness desired.

When it is desired to form a stucco or cement finish the outer sides of the boards or panels are formed with horizontally extending grooves or corrugations 18 to form 10 a firm interlocking support for the stucco or cement 19.

On account of the use of straw to form the insulating space 11 the composition board is comparatively light in weight and 15 may be made considerably thicker than the ordinary composition board without materially increasing its weight. The use of the straw also imparts desirable heat insulating qualities to the board.

20 The improved board may be sawed, nailed and handled in the same manner as ordinary lumber. While the specification and claims describes straw as forming the insulating portion it is to be understood that the word 25 straw is to be defined in a broad sense as covering any material of tubular form which might be used.

From the foregoing description it will be seen that the composition board is of very 30 simple construction and is well adapted for the purpose described.

What I claim as my invention is:

1. A composition board, consisting of an outer portion and an inner portion and an 35 interposed insulating portion formed of tubular parts, some of said tubular parts extending at right angles with relation to other tubular parts.

2. A composition board, consisting of a 40 thickness of material formed of asbestos and a plaster holding material and a medial insulating portion formed of straw or like material.

3. A composition board, comprising a 45 thickness of plaster material having two or more imbedded layers of straw extending at an angle with relation to each other and forming an insulating portion.

4. A composition board, comprising a 50 thickness of plastic material of one kind, a thickness of plastic material of another kind, and an interposed thickness of straw formed of several layers, some of which extend at an angle with relation to others, said plastic 55 materials extending between portions of the

straw and joined together to form an integral board.

5. A composition board, comprising a thickness of material formed of cement and asbestos, another thickness of material 60 formed of asbestos, plaster Paris and magnesia, and an interposed insulating portion formed of straw or like material imbedded in both thicknesses of material to form an integral board.

6. A composition board, comprising a 65 plastic board material having a medial insulating part formed of straw stems connected together by lines of stitches.

7. A composition board, comprising a 70 plastic board material having an inner medial insulating portion formed of straw stems or like material connected together by lines of stitches, the ends of the straw stems terminating within and covered by the 75 plastic board material.

8. A composition board, comprising a 80 plastic board material having an inner medial insulating portion formed of straw stems treated to make fire-proof and connected together by lines of stitches, the ends of the straw stems terminating within and covered by the plastic board material.

9. A composition board, comprising two 85 thicknesses of plastic board material joined together along one side face to form an integral structure, and layers of straw stems or like material stitched together and interposed between and imbedded in the thicknesses of material to form an insulating portion, and a waterproof coating on one side 90 portion of one of the thicknesses of material.

10. A composition board, comprising two 95 thicknesses of plastic board material joined together along one side face to form an integral structure. The outer face of one of the thicknesses of material being corrugated, and a layer of stitched together straw stems interposed between and imbedded in the thicknesses of material to 100 form an insulating portion.

11. A composition board, comprising a 105 plastic board material having a medial insulating portion formed of sections of sewed together straw stems, some of said straw sections extending at an angle with relation to other sections.

In testimony whereof, I affix my signature.
HENRY C. DORN.
